UNITED STATES PATENT OFFICE

2,087,472

SEALING MECHANISM FOR PACKAGING MACHINES

Harry Wilson Dyment, Cleveland, Ohio

Application December 30, 1935, Serial No. 56,825

13 Claims. (Cl. 216—22)

The present invention embodies improvements in machines designed for sealing packages or cartons wherein there is employed adhesive tape intended to be applied to the package or carton in such a manner as to partially encircle the same. The machine of the invention is particularly adapted for the final application of an adhesive or sealing tape to adjacent edges of closing flaps of a carton in such a manner that these edges 10 are effectively secured and sealed together, the tape additionally being caused to be folded about the ends of the carton and against the bottom thereof so as to make more effective the sealing action of said tape.

15 My improvements herein represent a carrying forward of the features of my invention of carton or package sealing machine of my copending application Serial No. 32,680, filed July 22, 1935, the improvements hereof dealing primarily with the 20 tape feeding, cutting, and applying devices.

While my previous machine works excellently for the purposes thereof, I have found that I am enabled to simplify somewhat the construction of the above noted features of the machine by 25 adopting a unit or carrier frame structure which supports the tape guiding, applying, cutting, and pressure devices, said carrier frame being susceptible, by a single adjustment, of adapting the 30 said various devices for operation upon a carton of predetermined thickness which is fed through the machine for the purpose of enabling the adhesive and sealing tape to be properly applied thereto.

My improvements hereof involve a novel form 35 of cutting mechanism, the operation of which is controlled in a somewhat different manner than heretofore proposed in my previous machine of the application aforesaid, and further involves improving devices for insuring the proper folding 40 and pressing of certain portions of the sealing tape against the ends of the package, or carton, whatever it may be, and the proper wiping of these ends of the tape into sealing engagement with the under-side of the package, at both of its 45 ends. I have found that these last mentioned operations of folding the tape against the ends of the package, pressing it into tight engagement therewith, and wiping certain free ends of the 50 tape when cut into proper sealed connection with the underside of the package, are somewhat delicate operations to be performed mechanically, but I have now designed mechanism of great efficiency for accomplishing these operations after the manner stated, and said mechanism with the control-

ling parts thereof constitute an important feature of the present invention.

My improved embodiment of my machine as above set forth is illustrated in the accompanying drawings, wherein—

5 Figure 1 is a partial top plan view of that portion of the machine which contains the improvements hereinbefore outlined.

Figure 2 is a side elevation of the parts of the machine that are illustrated in Figure 1.

10 Figure 3 is a top plan fragmentary view illustrating the control mechanism for operating the endless chain wiper device.

Figure 4 is a longitudinal sectional view showing more particularly the parts that are illustrated in Figure 3.

15 Figure 5 is a view of the rocking wiper device of Figure 2, illustrated in its upward position.

In describing my invention, the entire machine 20 thereof is not illustrated because I may employ the feeding hopper and mechanism for feeding the cartons therefrom as illustrated in my previous application, or any conventional mechanism for performing the same function. It will be understood, therefore, that my machine may comprise a main frame A, longitudinally of which 25 will be disposed a conveyer comprising spaced sprocket chains 1 and 2, these sprocket chains traveling in the direction of the arrows a shown in Figure 2. The conveyer chains 1 and 2 are 30 equipped with upwardly projecting lugs 3 at intervals in the lengths thereof, which lugs periodically engage a carton, box, or package 4 as the chains travel along the main frame A of the machine, several of said cartons being illustrated in Figure 35 2 at their different locations or spacings in the process of feeding the same through the machine. While the cartons or members 4 may be of box-like form, it is within the purview of the invention that the packages comprised thereby may 40 take other forms, this being immaterial to a disclosure of the present improvements.

The frame A carries lower pressure rollers 5 and upper pressure rollers 6 in contact with which the adhesive or sealing tape 7 passes. The tape 7 45 is fed from a suitable supply roll 8 underneath a guide roller 9, thence over a moistening brush 10 which moistens the under-adhesive side of the tape. From the moistener 10 the tape passes downwardly underneath a guide plate 11 to approximately the point where the tape is first applied to the adjacent carton, as seen in Figure 2, said carton moving under fixed pressure of the engaging lugs 3 of the conveyer chains 1 and 2 rightward or forward, according to the il- 50 55

lustration of Figure 2. The tape 7 is caused to be pressed downwardly and firmly against the upper side of the carton 4 by the upper rollers 6, and if the carton is of the type which has two longitudinal top closing flaps, the tape will be engaged with the adjacent edges of the flaps and span the space therebetween, if any. Three of the pressure rollers 6 act upon the tape to press it firmly against the upper side of the carton 4 as the carton moves from the position of the carton 4 at the left in Figure 2 to the position of the carton 4 in the middle of Figure 2.

The cartons to be sealed are moved through the machine in spaced relation with respect to each other, and the distance between succeeding cartons is dependent upon the distance between the adjustable lugs 3; the latter may be adjusted for handling cartons of various lengths.

The sealing tape applied to the cartons 4, 4a and 4b forms a membrane connecting said cartons. However, the sealing tape between cartons 4a and 4b has just been severed by the sealing tape cutting instrumentalities.

These cutting instrumentalities comprise a pivoted cutter control plate 12, the axis of which is shown at 13 (Figure 2). Secured to the axis 13 is a segment 14 having teeth engaging the teeth of a vertical rack and cutter bar 15 at the lower end of which is disposed the transverse cutter blade 16. It will therefore be seen that upward or downward movement of plate 12 around its axis 13 causes corresponding movements of the cutter blade 16. The upward movement is effected when a carton moving through the machine engages plate 12, while the downward movement of the blade takes place when the plate 12 slides off the carton while the latter proceeds in its movement to the right, see Figure 2.

From Figure 2 it will therefore be noted that the plate 12 has slid off the carton 4b and has dropped downwardly, causing a corresponding movement of bar 15 and blade 16, the latter severing the tape in the middle between cartons 4b and 4a. Such downward movement of parts 12, 14, 15, and 16 under the force of gravity positions plate 12 in such a manner as to be engaged and lifted again by the following carton 4a and a corresponding lifting of blade 16 is thereby produced. As long as the plate 12 is in engagement with the carton 4a the parts 12, 14, 15, and 16 are held in their upper position. When the carton 4a has proceeded so far to the right that plate 12 disengages from the same, the next cutting takes place. In this manner the cutting actions repeat while the cartons pass through the machine.

The length of the plate will have to be such as necessary to effect the cutting operation at the proper time.

A spring 17 may be provided to assist the gravitational movement of the control plate 12 and bar 15 in effecting the cutting action and to prevent locking between the teeth of members 14 and 15 when these members are in their upper position.

A pressure member 18, pivotally arranged at 19 within frame 43 and directly above the sealing tape, is provided. This pressure member 18 comprises an angular end 18a which rests upon the sealing tape on account of its own weight and which forces the sealing tape downwardly and in sealing contact with the end portion of the carton, so as to bend the tape around the corner of

the carton between its upper and forward end, see Figure 2, carton 4b.

When the tape is applied in this manner, the free end 18' will hang downwardly as clearly seen in Figure 2, this being desirable to permit an effective application of the free end of the sealing tape to the carton by a wiper 24 described later on.

Movement of carton 4a to the right from the position shown in Figure 2 will force the member 18 upwardly and the same rides upon the upper surface of the carton and sealing tape until the next following carton 4 approaches pressure member 18 and the tape cutting action between carton 4 and 4a takes place, whereupon member 18 acts to apply the free forward end of the tape to carton 4 now adjacent the same.

The action which forces the cut portion of the tape 7 at the right-hand end of the carton 4a, which is seen to be pendent in Figure 2 in relation to the middle carton 4, into firm engagement with the lower forward corner and bottom of the carton, is effected by the instrumentality of a wiper frame 20 rockingly pivoted at 21 and of somewhat U-form. The pivotal axis 21 of the wiper frame 20 is a shaft which carries an arm 22 actuated by a spring 23 so as to pull upwardly on the right-hand portion of the frame 20 to bring the frame 20 into the position shown in Figure 5, so that the wiper member 24, carried by the frame 20, will be in the path of movement of the carton 4a and will engage with the cut pendent portion of the sealing tape 7 at the front end of the carton so that as the carton progresses by the wiper member 24, the latter will wipe said free cut end of the tape against the lower forward corner and under-side of the carton or receptacle. A spring 25 cooperating with the member 24 permits the latter to yield downwardly and let the carton 4a travel forwardly as the member 24 performs its pressing or wiping function on the portion of the tape 7 described.

It is notable that the action of the wiper member 24 in initially applying the tape is supplemented by a further pressing or wiping action of wiper brush mechanism later to be described.

It will now be assumed that the carton 4a has progressed to the position of the right-hand carton 4b of Figure 2, after the cutting of the sealing tape between cartons 4 and 4a in the manner previously described, and is now ready for the final firm pressing of the sealing tape at the right-hand end thereof into engagement therewith. The final proper pressing of the pendent cut portion of the tape 7 at the left-hand end of the carton into sealing contact therewith is likewise to be treated.

The above two actions are accomplished in the following way.—As the carton 4a, which may now be called carton 4b because the same is in the proper position for the purposes of the following description, extends beneath an applicator roller 26, this roller, because it is made of sponge rubber and because its periphery is somewhat below the plane of the upper side of the carton 4b, effectively forces the tape 7 at the left-hand end of the carton and at the upper left corner into firm engagement with the said corner and the top portion of the end. This action is highly desirable in obtaining an effective action of applying the sealing tape to the left-hand portion of the package or carton.

The wiper mechanism previously mentioned consists of a series of wiper brushes 27 carried by the endless chains 28 which pass around sprocket 75

wheels 29 and 30. The sprocket wheels 29 are carried by a shaft 31 which also carries a small gear wheel 32. The gear wheel 32 is meshed with a rack 33 slidably mounted in a frame or guide 32'. said rack being connected by a link 34 with an arm 35 offstanding from a forward wipe lever 36. The lever 36 is connected by a link 38 with the back wipe lever 39. The lever 39 is pivoted at 40 to a suitable supporting member of the frame, 10 while lever 36 is pivoted to the frame A at 39'.

The forward wipe lever is so called because it is an actuating lever for imparting movement to the rack 33 to cause a rightward movement of said rack turning the gear 32 in a clockwise manner as shown by the full line arrow of Figure 4. This turning of the gear 32 is effected with such speed that a quick actuation of the chains 28 carrying the wiper brushes 27 to be shifted from the position of Figure 2 around the sprocket wheel 29 into engagement with the pendent cut portion of the tape 7 at the left-hand end of the carton 4b. In this way the wiper brushes 27 press firmly and quickly against the said pendent cut portion of the tape 7 and thus apply it firmly to the end and bottom portions of the carton 4b at the left end of the latter. While the brushes move toward the right end of the carton the tape previously applied by wiper 24 is additionally pressed into firm adhesive contact with the carton, then the brushes pass from beneath the carton at its right side and partially around the sprocket wheels 30 from where they immediately return backward to their original position, as will be clearly understood from the following. The actuation of the chain 28 and the wiper members 27 in the above manner, through actuation of the rack 33 and gear 32 is caused by one of the abutment lugs 3 which cooperate to feed the cartons 4, 4a, and 4b on the conveyor chains 1 and 2 engaging with the forward wipe lever 36 in the manner which is shown in Figure 3. In this figure the lug 3 is just about to strike the wipe lever 36 and cause it to move into the dotted line position illustrated, so as to accomplish what is termed herein 45 the forward wiping action of the brush 37.

This brings us to the back-wipe action of the brushes 27 by which is meant that these brushes are given a movement in a direction opposite that previously described, so that they will turn about the right-hand sprocket gear 30, while carried by the chain 28, and will have a back-wiping action on the portion of the tape at the front end of the carton 2 beneath the front end portion thereof. The purpose of this back wiping action is to supplement the sealing applying action of the tape which is performed by the brushes 27 upon their forward movement, previously described, and the wiper member 24, the operation of which has been set forth.

Bearing in mind that the forward wipe lever 36 is connected to the back wipe lever 39, when the lever 36 reaches the dotted line position shown in Figure 3, the lug 3, that has caused it to move to such position, escapes therefrom by passing over the end of the lever.

The lug 3 now engages lever 39 which has moved from its full to the dotted line position in Figure 3 by the action of the lever 36 with which it is interconnected by a lever 38. Lug 3 shifts lever 39 now back to full line position, causing movement of rack 33, gear 32, and sprocket gears 29 and 30 in an opposite direction to that mentioned and specifically described heretofore, and the brushes 27 are thereby returned from adja-

cent sprocket gears 30 to their original position, as shown in full lines in Figure 2.

The wiping unit 20 is connected by means of a lever 22 and spring 23 to lever 36, and upon movement of lever 36 to its dotted line position in Figure 3, the spring is tensioned, which causes the elevating of the wiping unit to the position shown in Figure 5, and as hereinbefore described. The arrangement is such that the unit 20 will be raised sometime before the respective carton, adjacent unit 20, has passed the same.

From the foregoing it will be seen therefore that the wiper mechanism comprising the brushes 27 is a reversibly operable device, being first actuated to firmly apply the front cut end of the tape at the left hand end of the carton 4b to the end and bottom of the carton, and thereafter cause a final firm pressing and engagement of the corresponding right-hand end of the tape to the right-hand end and bottom of the carton, supplementing the previous application of this portion of the tape thereto.

Upon reference to Figure 2 it will be seen that after the carton 4b has passed the applicator roller 26 and the final pressing roller 41, the action of completely applying the sealing tape thereto is accomplished and the carton completely sealed passes through a final pressure shoe 42 of such a machine upon a conveyer or into a hopper or any suitable packaging receptacle.

One of the important phases of my invention has been to utilize an auxiliary adjustable frame 43 which carries the moistener 10, the rollers 6, the cutter bar 16, and its blade 16, the applicator roll 26 of sponge rubber, and the final pressing roller 41 and shoe 42. The said auxiliary frame 43 is carried by a vertical standard 44 and is adjustable so as to be raised and lowered by a screw or any suitable manual means 45. In this way all the various operating parts described as being carried by the frame 43 will be vertically adjusted in proper spaced relation to the conveyer chains 1 and 2, the vertical adjustment being intended to accommodate for feeding through the machine between the said parts, and the conveyer chains 1 and 2, of cartons, packages, boxes, or the like, of different vertical thicknesses. It will be apparent from Figure 2 that the standard 44 will be carried by a yoke or some other portion 46 of the main frame of the machine, and the supporting arms 47 for the sealing tape roll 8 are likewise carried by a yoke 46.

The levers 36 and 39 extend into the path of the lugs 3 through a slot 40' in the chain guide member 40". This slot is of sufficient length to permit the free operation of said levers as will be clearly understood from Figure 3.

Having thus described my invention, what I claim as new and desire to secure by Letters Patent of the United States, is—

1. In a machine for applying sealing tape to cartons, carton conveying mechanism, a main frame supporting the conveying mechanism, and means for pressing the tape against the forward traveling end of the carton on the conveyer, including a pressure plate having an angular portion to press the tape against the front upper corner portion of the front end of the carton as the carton progresses through the machine of the conveyer.

2. A machine as claimed in claim 1, combined with a cutter bar control plate, and a cutter bar interconnected with the control plate and movable in accordance with the movement of the latter, said control plate being disposed in the

path of travel of the cartons moved by the conveyer and movable downwardly when disengaged from said cartons to cause effective operation of the cutting bar.

5 3. In a machine for applying sealing tape to cartons or the like, in combination, a main frame, carton conveyer means thereon for moving cartons through the machine, sealing tape applying means for affixing sealing tape to the carton 10 lengthwise thereof at the top portion, cutting mechanism for cutting the tape so that pendent portions of the tape extend downwardly of the ends of the carton from the top thereof, and reversible mechanism for imparting a forward wiping applicator contact of the pendent portion of the tape at the rear end of the carton, to the 15 said end and bottom of the carton, and for correspondingly causing a wiping applicator contact of the pendent end of the tape at the front end of the carton to the bottom portion of the 20 carton.

4. A machine as set forth in claim 3, combined with devices carried by the conveyer for controlling the reversible action of the said wiper 25 mechanism.

5. In a machine for applying sealing tape to cartons or the like, in combination, a main frame, a conveyer movable therealong for carrying cartons through the frame, adhesive tape applicator 30 means for applying an adhesive tape to seal the cartons, cutting mechanism for cutting the tape after the same has been applied to the top of the carton so that the opposite portions of the tape are pendent from the ends of the carton, positive 35 means to press the said pendent portions of the adhesive tape against the ends of the carton at the upper corner portions of the ends, and reversible wiping mechanism shiftable in one direction to wipe the pendent portion of the tape at the rear end of the carton against the said rear end and bottom of the carton, and to wipe the pendent portion of the tape at the front end of the 40 carton against said front end and bottom of the carton.

45 6. A machine as claimed in claim 5, in which the positive means for applying the tape to the upper corner portions of the ends of the carton includes a preliminary operating wiper member acting on the pendent portion of the tape at the front end of the carton.

50 7. A machine as claimed in claim 5, in which the positive means for applying the tape at the upper corner portion at the front and rear ends of the carton includes a pressure roller of sponge 55 rubber, the periphery of which is located below the plane of the path of travel of the upper side of the carton.

60 8. In a machine for applying sealing tape to cartons or the like, in combination, a carton conveyer, a sealing tape applicator mechanism for applying sealing tape to cartons traveling on said conveyer, means to cut the sealing tape so that pendent portions thereof depend past and from the ends of the carton which is being sealed by the tape, and a reversible wiper mechanism comprising wiper parts shiftable in opposite directions to first wipe one depending end of the tape against an end and bottom of the carton, and thereafter press against the opposite end of the 65 tape applied to the carton.

70 9. In a machine for applying sealing tape to cartons or the like, in combination, a carton conveyer, a sealing tape applicator mechanism for applying sealing tape to cartons traveling on said conveyer, means to cut the sealing tape so that 75

pendent portions thereof depend past and from the ends of the carton which is being sealed by the tape, a reversible wiper mechanism comprising wiper parts shiftable in opposite directions to first wipe one depending end of the tape against 5 an end and bottom of the carton and thereafter press against the opposite end of the tape applied to the carton, said reversible wiper mechanism including an endless chain, wiper brushes on said chain, and means for imparting an accelerated movement to the chain in opposite directions to cause a corresponding movement of the wiper parts.

10. In a machine for applying sealing tape to cartons or the like, in combination, a carton conveyer, a sealing tape applicator mechanism for applying sealing tape to cartons traveling on said conveyer, means to cut the sealing tape so that pendent portions thereof depend past and from the ends of the carton which is being sealed by 15 the tape, a reversible wiper mechanism comprising wiper parts shiftable in opposite directions to first wipe one depending end of the tape against an end and bottom of the carton and thereafter press against the opposite end of the 20 tape applied to the carton, said reversible wiper mechanism including an endless chain, wiper brushes on said chain, and means for imparting an accelerated movement to the chain in opposite directions to cause a corresponding movement of the 25 wiper parts, comprising a forward wipe lever operatively connected with said chain, and a back wipe lever operatively connected with the chain, together with instrumentalities for 30 timing the action of said levers from the conveyer means.

11. In a machine for applying sealing tape to cartons or the like, in combination, carton conveyor means for moving cartons through the machine, sealing tape applying means to supply and 40 affix sealing tape to the carton lengthwise thereof at its top portion, instrumentalities for cutting the tape so that pendent portions thereof extend downwardly at the ends of the carton from the top thereof, means for preliminarily applying the 45 front cut pendent portion of the tape to the lower front corner and bottom portion of the carton, comprising a wiping instrumentality to contact the tape and wipe it into sealing connection with the carton, and mechanism acting upon said 50 front cut portion of the tape after it is wiped into contact with the carton to subsequently press said portion of the tape against the part of the carton to which it is applied.

12. In a machine for applying sealing tape to cartons or the like, in combination, carton conveyer means for moving cartons through the machine, sealing tape applying means to supply and affix sealing tape to the carton lengthwise thereof at its top portion, instrumentalities for cutting the tape so that pendent portions thereof extend downwardly at the ends of the carton from the top thereof, means for preliminarily applying the front cut pendent portion of the tape to the lower front corner and bottom portion of the carton, comprising a wiping instrumentality to contact the tape and wipe it into sealing connection with the carton, and mechanism for imparting a forward wiping applicator contact of the pendent portion of the tape at the rear end of the carton to the adjacent end and bottom portions of the carton and including wiper parts to act on the tape as above stated, together with operating devices for reversely moving said applicator 75

cator parts to cause a wiping contact of the same on the front cut pendent portion of the tape to accomplish for a second time the firm pressing of this portion of the tape in contact with the bottom of the carton.

5 13. A machine as claimed in claim 12, combined with devices for causing the last mentioned ap-

plicator parts to move in reverse directions in order to effect their wiping contacts with the front and rear portions of the tape in applying the latter to the front, rear, and bottom portions of the carton.

HARRY WILSON DYMENT.

5
